UNITED STATES PATENT OFFICE.

FELIX GUT, OF HOTTINGEN, NEAR ZURICH, SWITZERLAND.

DRILLING-MACHINE.

SPECIFICATION forming part of Letters Patent No. 328,886, dated October 20, 1885.

Application filed August 22, 1885. Serial No. 175,050. (No model.)

To all whom it may concern:

Be it known that I, FELIX GUT, of Hottingen, near Zurich, Switzerland, have invented a new and useful Improvement in Boring-5 Drills, of which the following is a specification.

This invention relates to an improved boring-drill for enlarging the inner ends of the rivet or bolt holes of boilers, tanks, &c., from the outside, so as to dispense with the inconvenience connected with enlarging the holes in the confined space at the inside of the boiler or tank; and the invention consists of certain 10 details of construction and combination of parts, which will be described hereinafter, and finally pointed out in the claims.

In the accompanying drawings, Figure 1 represents a side elevation of my improved boring-drill. Fig. 2 is a vertical central section of the same; and Figs. 3, 4, and 5 are details 15 of parts of the same.

Similar letters of reference indicate corresponding parts.

In the drawings, *a* represents the spindle of a boring-drill, which is screwed or otherwise secured into a socket-piece, *p*. To the end of the spindle *a* is splined a conical boring or drilling tool, *b*, which is set against a shoulder of the spindle, and secured by means of a spring-key, *d*, that is passed through a transverse hole, *e*, at the end of the spindle *a*. The socket-piece *p* is provided with a longitudinal groove, *p'*, for the spline *q'* of a ratchet-wheel, *q*, which is engaged by a spring-actuated pawl, *r*, that is located in a socket-shaped recess of an oscillating lever, *f*. The socket-piece *p* is connected with a screw-nut, *m*, by a coupling-piece, *o*, which latter is keyed to the socket-piece and seated by its enlarged head in the lower contracted part of the nut *m*. The nut 35 *m* is guided by longitudinal grooves *m'* on fixed guide-pins *n n* of the tubular casing *A*, within which the socket-piece *p* and its nut *m* are located.

A screw-bolt, *l*, passes through the casing 45 *A* down into the nut *m*, and is provided with levers *g g*, that are retained on the outer end of the screw-bolt *l* by a nut and washer, *l'*.

To the upper end of the casing *A* is attached a guide-disk, *h*, by means of screws *h'*, said disk 50 being recessed for guiding the shoulder *l'* of the screw *l*.

Below the disk *h* is arranged a guide-disk,

k, which bears against the shoulder *l'*, and which retains, together with the disk *h*, the screw *l* in position in the casing *A*. 55

Between the disk *h* and the levers *g g* are interposed two spring disks or plates, *i i*, which plates exert a tension on the levers, so as to cause the turning of the screw *l* with the levers *g*. 60

By turning the levers *g* the screw *l* is turned, and the nut *m* moved up, whereby the spindle *a* and drilling-tool *b* are drawn into the rivet or bolt-hole, so as to be ready to operate on the inner end of the hole to be drilled out. 65

The casing *A* and nut *m* are provided at opposite sides with elongated openings, by means of which the socket-piece *p* can be held in position in a vise when it is desired to remove the spindle *a* from the socket-piece *p*. These openings also serve for inserting and removing the connecting-piece *o*. 70

The boring-drill is worked as follows: The spindle *a* is inserted from the outside into the rivet or bolt hole of the boiler, tank, or other plate and the drilling-tool *b* applied to the spindle by the spring-key *d*. The boring-tool *b* is then drawn up against the inner edge of the hole to be enlarged by turning the levers *g g*, which turn the screw *l*, and move the nut *m* and socket-piece *p* into the hole of the plate, while the casing *A* rests by its base on the outside of the same. The lever *f* is next oscillated and the hole drilled out by the tool *b*. The levers *g g* are turned from time to time, so 85 that the boring-tool is fed forward into the hole until the same is enlarged to its full extent, as required for the head of the rivet or bolt. The boring-tool is then removed from the spindle, and the latter inserted into the 90 next hole, after which the boring-tool is secured again to the spindle, and the hole enlarged, as described.

Having thus described my invention, I claim as new and desire to secure by Letters Patent— 95

1. The combination of the tubular casing *A*, guide-disks *h* and *k*, screw *l*, having shoulder *l'* and levers *g g*, spring-disks *i i*, interior screw-nut, *m*, socket-piece *p*, coupling-piece *o*, ratchet *q*, oscillating lever *f*, having a spring-actuated 100 pawl, *r*, and spindle *a*, having a detachable boring-tool, *b*, substantially as set forth.

2. The combination of a tubular casing, *A*, having guide-screws *n n*, guide-disks *h* and *k*,

screw *l*, having shoulder *l'* and levers *g g*,
spring-disks *i i*, screw-nut *m*, having guide-
grooves *m'*, socket-piece *p*, coupling-piece *o*,
and spindle *a*, having a detachable boring-tool,
5 *b*, substantially as set forth.

3. The combination, of a tubular casing, *A*,
having guide-screws *n n*, screw *l*, screw-nut *m*,
having guide-grooves *m'*, socket-piece *p*, having
groove *p'*, coupling-piece *o*, spindle *a*, hav-
10 ing boring-tool *b*, ratchet *q*, having spline *q'*,
and oscillating lever *f*, having a spring-act-
uated pawl, *r*, substantially as set forth.

4. In a boring-drill, the combination of a
spindle having a shoulder, a detachable bor-
15 ing-tool splined to the spindle, and a spring-

key inserted into a transverse recess at the end
of the spindle, substantially as set forth.

5. In a boring-drill, the combination of the
tubular casing *A*, socket-piece *p*, ratchet *q*,
oscillating lever *f*, and a spring-actuated pawl,
20 *r*, located in a socket-hole of said lever, sub-
stantially as set forth.

In testimony whereof I have signed this
specification in the presence of two subscrib-
ing witnesses.

FELIX GUT.
